United States Patent Office

Des. 219,210
Patented Nov. 17, 1970

219,210

CIRCULAR PALLET

Leonard E. Hall, Rochester, N.Y., assignor to Eastman Kodak Company, Rochester, N.Y., a corporation of New Jersey

Filed Nov. 21, 1969, Ser. No. 20,220

Term of patent 3½ years

Int. Cl. D12—99

U.S. Cl. D14—3

FIG. 3

FIG. 2

FIG. 1

FIG. 1 is a perspective view of a circular pallet showing my new design:

FIG. 2 is a top plan view:

FIG. 3 is a side elevational view.

The broken line showing how an article is supported by the pallet is for illustrative purposes only.

I claim:

The ornamental design for a circular pallet, as shown.
